ABSTRACT

A vehicle lamp assembly comprises a dished reflector in which is disposed a filament. The filament is disposed at an angle, preferably 30° to 45°, to a horizontal plane in which a principal axis of the reflector lies. The filament may lie with its axis perpendicularly disposed with respect to the principal axis. The lamp assembly may further include a parabolic mirror or lens spaced from the reflector and a mask between the reflector and the mirror or lens.

FIG. 1.

FIG. 2.

VEHICLE LAMP ASSEMBLIES

This invention relates to vehicle lamp assemblies.

According to the present invention, there is provided a vehicle lamp assembly comprising a dished reflector, and an electric filament disposed in said dished reflector, said electric filament having an axis which extends transversely with respect to a principal axis of the reflector and which is inclined with respect to a horizontal plane in which the principal axis lies.

Preferably, the filament is inclined at an angle of between 30° and 45° inclusively, with respect to the said horizontal plane.

Most advantageously, the axis of the electric filament lies perpendicularly with respect to the principal axis of the reflector.

The vehicle lamp assembly may further include optical projection means arranged to receive and optically modify the pattern of light issuing, in use, from the dished reflector.

The electric filament may be a conventional metal filament or a quartzhalogen filament.

Conveniently, a mask is provided in front of the reflector to modify the pattern of light issuing, in use, from the reflector. The mask may be provided between the reflector and the optical projection means.

The optical projection means may be a lens or lenses, or it may be a curved reflector e.g., a parabolic mirror.

The inclination of the electric filament in the above described manner enables the image of the filament to be aimed, in use, along a roadside curb which improves the characteristics of the lamp assembly as far as the driver's visibility is concerned.

An embodiment of the present invention will now be described, by way of example, with reference to the accompanying drawing, in which:

FIG. 1, is a schematic view of a vehicle lamp assembly according to the present invention, and

FIG. 2, is a schematic front elevation view of a lamp reflector used in the lamp assembly of FIG. 1.

Referring to the drawing, the vehicle lamp assembly, which is for use as a vehicle headlamp of the dipped type, comprises generally a dished reflector 10, a generally rectangular convex lens 11 spaced axially from the reflector 10 and having its principal axis lying on the principal axis of the reflector 10, and a mask 12 extending perpendicularly with respect to the principal axis of the reflector 10. Mounted within reflector 10 in an inner focal plane thereof is a tungsten filament 14 which extends perpendicularly with respect to the principal axis of reflector 10 and which has an axis lying at

an angle to a horizontal plane in which the reflector principal axis lies. The angle, designated α in FIG. 2 may be between 30° and 45° but, in this embodiment, is 35°.

5 The mask 12 has an upper edge 15 which is disposed just below the principal axis of the reflector 10.

In use, the light pattern emanating from filament 14 and reflector 10 is modified by the mask 12 before passing through lens 11 in such a manner that an upper

10 portion of the light pattern which would otherwise emerge from lens 11 is cut off. The provision of the mask 12 enables the lamp assembly to be used as a so-called dipped headlamp on a vehicle. The angling of the filament 14 relative to the principal axis of reflector

15 10 in the manner described above enables the image of the filament projected by the lamp assembly to be aimed along a roadside curb which the lamp assembly is fitted to a motor vehicle. Aiming of the filament in this manner is considered to improve the visibility of 20 the curb at least as far as the driver of the vehicle is concerned.

The lamp assembly described in the present application is particularly suitable for use with the curved reflector described in our co-pending British patent application No. 25248/73 dated May 25, 1973.

By the expression "horizontal plane" as used herein with respect to the positioning of the filament relative to the reflector is meant the positioning of the filament when the reflector is in an orientation corresponding to 30 that in which it is designed to be used.

We claim:

1. A vehicle lamp assembly comprising a dished reflector which is at least partially ellipsoidal in shape and has an inner focal plane and an optical axis, and an 35 electric filament disposed in said dished reflector at said inner focal plane thereof, said electric filament having an axis which extends transversely with respect to a horizontal plane containing the optical axis of the reflector, said filament being inclined at an angle of 30° to 45° inclusive with respect to said horizontal plane.

2. An assembly as claimed in claim 1 wherein said filament extends in a plane perpendicular to said optical axis.

3. An assembly as claimed in claim 1, further including optical projection means arranged to receive and optically modify the pattern of light issuing from the dished reflector.

4. An assembly as claimed in claim 1 comprising a mask in front of the reflector to modify the pattern of 50 light issuing, in use, from the reflector.
